INCLINOMETER

Philip Jones, Los Angeles, Calif.

Application June 26, 1944, Serial No. 542,056

11. Claims. (Cl. 33—205.5)

1

This invention relates to improvements in apparatus for measuring and recording the inclination of bore-holes, as for example oil wells.

In applicant's Patent 2,246,519, reference is made to devices in which the record of instrument position is made by mechanical means, these means including a watch mechanism.

In the present invention, the disadvantages inherent in such timing devices are avoided by the adoption of an electrically operated inclinometer (drift recorder) unit, in conjunction with controlling means by which the functioning of the inclinometer is delayed until the device is brought to rest at the point at which the record of inclination is desired—usually at the bottom of the hole.

An illustrative embodiment of the invention is shown in the accompanying drawings, in which:

Fig. 1 is a vertical section through the inclinometer unit;

Fig. 2 is a plan view, looking upwardly, of the plunger, conducting ring and contact points as on the line 2—2 of Fig. 1;

Fig. 3 is a vertical section through the control assembly;

Fig. 4 is a vertical section through the vibrator assembly;

Fig. 4A illustrates an alternative form of the vibrator;

Fig. 5 is a diagram showing preferred electrical circuits by which the elements of the control assembly are functionally connected;

Fig. 6 is a diagram illustrating modified circuits by which the control mechanism may be adapted to the making of a photographic record, and

Fig. 7 is an elevation of a complete assembly in a suggested order of arrangement of the above elements.

Referring first to Fig. 1, a housing tube 10 contains a pendulum bob 11 suspended from a cap 12 by a chain 13. The bob is provided with a dull point as at 14.

An extension tube 15, screwed into tube 10, contains an electromagnet consisting of a solenoid coil 16 and a vertically movable core or plunger 17, from the upper end of which a nonmagnetic extension 18 is projected upwardly. Above the solenoid is placed a vertically slideable table 19, to the upper surface of which is fastened (as by cementing) a disc 20 of inked ribbon or of carbon paper with its inked surface upward.

Below the solenoid is fixed a disc 21 of non-conductive material (e. g., Bakelite) in which are inserted three contact points 22—22. The lower end of plunger 17 flexibly supports, as by means

2

of a spiral spring 23, a conducting ring 24 by means of which the contact points are electrically connected on upward movement of the plunger, for a purpose which will be described.

5 The above elements are so proportioned that when tube 15 is screwed home in tube 10 the point 14 of bob 11 swings slightly above the surface 20. On energization of magnet 16 the plunger 17 moves upwardly and extension 18 encounters the 10 lower side of the table, driving it upwardly and into sharp contact with point 14. A disc of plain paper having been concentrically placed on the inked surface 20, an inked impression on the lower face of the paper disc indicates the existing 15 position of the point of the bob as regards the center of the paper disc and, thus, the momentary inclination of the instrument.

Referring next to Fig. 3, a solenoid 25 is wound around the upper end of a nonmagnetic tube 26 20 which is plugged at the upper extremity as at 27. Inside this tube is a hollow piston (or piston tube) 28 having at its lower end a nonconductive coupling 29. The lower end of this coupling is faced, to provide at 30 a seat for a valve 31 of slight 25 weight which is gently urged against its seat by a light coil spring 32.

To the lower end of coupling 29 is fixed a valve cage 33 which is slotted as at 34, the lower end of the cage being open. Across the lower end of 30 the cage is fixed a tube 35 containing two small steel balls 36—36 which are urged apart by an open coil spring 37.

To the lower end of tube 28 is screwed a flange 38 and a blind flange 39 is drawn toward it by 35 a plurality of bolts 40—40. Between these flanges are clamped a plurality of rings or short tubular sections 41—41 of conductive material, these sections being separated and insulated by short spacing rings 42—42 of nonconductive material. 40 These elements are so formed and mated as to produce a liquid-tight extension of insulating tube 26.

The tube 35 above described is so inclined to the horizontal that its contained balls and spring 45 act as a brush to make contact simultaneously with adjacent conductive rings 41—41. Any other form of brush member arranged to make such contacts may be substituted. The assembly of rings 41 and 42 and tube 26 forms a reservoir 50 which is filled with a light and nonviscous oil such as kerosene.

This unit functions in the following manner. On energization of solenoid 25 the piston tube 28 is drawn upwardly, this movement being substantially unopposed by the liquid, which escapes

through downwardly opening valve 31. Upon de-energization of the solenoid, however, the piston assembly can descend only at the rate permitted by leakage past the valve or piston or, in practice, through a minute port such as the orifice indicated at 43. Assuming that this leakage occurs, upon descent of the piston assembly, insulating rings 42 are successively bridged by the brush balls 36, establishing electrical contact between successive pairs of adjacent conductive rings 41.

Referring now to Fig. 4, an aligning tube 44 is provided at its upper end with an insulating bushing 45 and at its lower end with a conductive ring 46. A vibrator consisting of a spring wire 47 and a weight 48 is suspended from bushing 45, the wire passing through a hole 49 in ring 46. These elements are so proportioned that no contact is made between wire 47 and ring 46 when the device is at rest in an approximately vertical position (i. e., within the range of vertical inclination to which the specific instrument is adapted) but so that such contact is momentarily made upon acceleration of the device, such as occurs in running it into the hole.

The above form of vibrator assembly is responsive mainly to lateral movement of the device, the wire 47 being substantially rigid vertically. The modified form shown in Fig. 4A is responsive to acceleration in any direction and may be used if preferred. Referring to this figure, the weight 48 is suspended by a sensitive coil spring 50 in such manner as to clear the inner surface of a conductive cup 51 when the instrument is at rest in an approximately vertical position, contact between the weight and the cup being produced by any change in velocity, either longitudinal or lateral.

The physical assembly of the device, as a whole, includes the three units above described, three relays and a battery consisting of dry cells, all of which may be contained in tube 15 and be arranged in any convenient order, there being no mechanical connection between the various units. The electrical connections by which the elements are brought into functional cooperation are shown in an exemplary form in Fig. 5. This is a conventional circuit diagram in which numbered elements correspond to parts already described and F, G and H are the three relays just referred to.

The functional operation of the apparatus is as follows: assuming that the piston assembly 28/32 has in some manner been brought to the position indicated in Fig. 3, the brushes 36 are in the position indicated by the dotted bridge 38a (Fig. 5), the segment 41A is grounded and relay F is short-circuited and therefore open. With this relay open, no current flows through solenoid coil 25 and the piston assembly 28/32, carrying brushes 36, descends by gravitation at a rate determined by the liquid flow rate through orifice 43.

As the brushes pass over segments 41A—41B, no relay is energized, and piston descent continues until the brushes reach the position 38b, in which segments 41B—41C are connected. It will be noted that segment 41B is connected to one terminal of the vibrator (Fig. 4 or 4A) of which the other terminal is connected to one terminal of the winding of relay F, the other terminal of this relay being grounded. Also that segment 41C is connected to the "live" battery terminal, the other terminal of the battery being grounded.

If, therefore, during the passage of the brushes over segments 41B—41C, the vibrator contacts

are closed by movement of the device as above described, the circuit through relay F is completed. Upon the consequent closure of relay F, circuit is completed through solenoid 25 and through a resistor J to the relay winding as shown. The piston assembly is thereby restored to its initial (elevated) position, the relay contact being held closed by current passing through resistor J, regardless of any contacts at 41B—41C and in the vibrator during this restoration. When the brushes reach their initial position 38a) the winding of relay F is again short-circuited and the initially described circuit conditions are restored: i. e., the magnetic force tending to hold the piston at the upper end of its stroke is removed and the piston is again free to descend.

This descent of the piston to the brush position indicated at 38b and the return of the piston to its initial position are repeated during the lowering of the device into the hole, the assembly being subject to acceleration and vibration during this descent, whereby frequent momentary contacts are made in the vibrator assembly.

When the device finally comes to rest—as when, in practice, it reaches the bottom of the hole or other level at which inclination is to be measured—the vibrator contacts remain open, the piston is not retrieved as the brushes pass over segments 41B—41C, and the brushes consequently pass on to position 38c at which segments 41C and 41D are connected. When this contact is made, relay G is closed and is thereafter held closed, independently of the contact 41C—41D, by current flowing through a parallel resistor K as in the case first described. The brushes then continue their descent to the position 38d, connecting segments 41D—41E.

In this position of the brushes, the windings 40 of relays G and H are in parallel. Relay H therefore closes and energizes solenoid 16 of the inclinometer unit (Fig. 1).

Upon the resulting upward stroke of plunger 17, the record on the paper disc is made as described and, simultaneously, ring 24 is brought into contact with the three contact points 22—22, which are connected respectively to the "live" terminals of relays G and H and to ground. These relays are thereby short-circuited and consequently open. Upon the opening of the contact at relay G, these relays can no longer be energized, as before, via resistor K of relay G, so that no repetition of the recording operation will thereafter occur.

In the working instrument, the several units are housed in a tubular shell, portions of which are indicated at 10 and 15 in Figs. 1 to 4A inclusive. This shell is jointed at suitable points to afford access to the several units. These may be arranged in any convenient vertical order, though preferably with the inclinometer unit (Fig. 1) at the upper end. A suggested arrangement, which may be modified at will, is indicated in Fig. 7.

In its use in the field, the operation of the instrument is typically as follows: assuming that the position of the piston assembly is that last above described (i. e., at the lower end of its stroke) as it will be, ordinarily, at the end of a previous recording, the operator proceeds thus: Holding the device horizontally or generally right end up, he inserts a record disc over the inked surface 28 of table 18 of the inclinometer unit and encloses the entire instrument in any suitable pressure-tight housing. These housings are well

known in the art and need no description. At any convenient time thereafter, the whole assembly is turned wrong end up for a moment, allowing fluid to pass valve 31 (Fig. 3) and the piston assembly to return to the upper end of its travel by its own weight.

When the assembly is restored to its normal position it is immediately lowered into the well, either at the end of a line or by dropping freely as in a go-devil.

Referring again to the wiring diagram Fig. 5, it will be seen that, upon inversion of the instrument, the brushes first move to position 36c, in which segments 41C—41D are connected. This, as before, closes relay G, which is thereafter held closed by current via resistor K, the "make" contact at relay G and the "break" contact at relay F. Upon the first operation of relay F, almost immediately thereafter, this circuit is opened at the "break" contact of relay F. Relay G thereupon opens and is not again closed until the brushes again, in their downward travel, reach position 36c at which segments 41C and 41D are connected.

As the apparatus is lowered or dropped into the well, the vibrator contacts are repeatedly closed in response to the many shocks incident to its motion. Thus the piston is retrieved repeatedly, as above described, and cannot reach the position at which solenoid 16 is brought into function and the record is made until the apparatus comes to rest.

After the recording operation is completed it is immaterial what is done with the instrument: whether it is immediately withdrawn or is recovered when the drill pipe is run out. No other record can be produced until after the device is again inverted and the relays consecutively operated in the order stated.

Although the description so far has been with respect to an electromagnetically operated inclinometer unit, the method of control herein described may be adapted to inclinometer units of other types, as for example the photographic unit described in applicant's U. S. Patent 2,246,519.

Such an adaptation is illustrated in the circuit diagram Fig. 6, which is largely self-explanatory. In this modification, relay H is omitted and a lamp M (which may be the lamp 11 of the patent) is connected to the "make" contact of relay G. In this adaptation, relay G is energized, as before, when the brushes reach position 36c; the lamp is consequently energized. The relay winding is short-circuited at the final brush position 36d and the lamp is extinguished. For the reasons above given, this operation will not be repeated until the device is again inverted. Thus the patented instrument referred to is made adaptable to go-devil operation, as is referred to at line 34, page 4 of the patent.

I claim as my invention:

1. In an inclinometer having a pointed pendulum, a sliding table and electromagnetic means for driving said table against said point to produce a record of point position on a record element placed on said table; means for controlling the operation of said electromagnetic means, comprising: a solenoid coil wound on a tubular element closed at its lower end to provide a reservoir for a nonconductive liquid; a hollow piston of magnetic material reciprocating in said tubular element; a downwardly opening valve closing the bottom of said piston and means to produce slow leakage around said valve; a series of contact points longitudinally arranged in the wall

of said reservoir; brush means moving with said hollow piston to connect said points in consecutive pairs; means for energizing said solenoid to maintain said hollow piston in a relatively elevated position so long as said inclinometer is subject to acceleration, and means functioning when the lowermost pair of said points is bridged to energize said electromagnetic means to produce said record.

- 10 2. In an inclinometer having a pointed pendulum, a sliding table and electromagnetic means for driving said table against said point to produce a record of point position on a record element placed on said table; means for controlling the operation of said electromagnetic means, comprising: a sealed reservoir containing a liquid; a piston arranged to be raised by a solenoid and to subside slowly through said liquid by gravity; contact points arranged in the wall of said reservoir and brush means carried by said piston and arranged to connect said contact points in pairs; a vibrator unit affording electrical contacts on acceleration thereof; an electric circuit including said vibrator unit, said solenoid and one pair of said contact points, whereby on the connecting of said points by said brush means said piston is retrieved and held in a relatively elevated position so long as said inclinometer is subject to acceleration, and a second electrical circuit arranged to energize said electromagnetic means and to produce said record when said inclinometer comes to rest and said piston subsides to bring said brush means into contact with a second pair of said contact points.
- 15 3. Means for timing the record-producing element of an inclinometer, comprising: a solenoid and a core arranged to be elevated thereby and to subside slowly when said solenoid is deenergized; an upper and a lower pair of contact points and brush means moving with said core and arranged to bridge said points in pairs; means responsive to acceleration of said inclinometer for completing an electrical circuit through said upper pair of points whereby said solenoid is energized and said core is maintained in a relatively elevated position so long as acceleration continues; a second electrical circuit including said lower pair of points and said record-producing element whereby said element is energized and said record produced when acceleration ceases and said core subsides to its relatively lower position.
- 20 4. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated position so long as said acceleration recurs; means cooperating with said brush means to complete a second electrical circuit energizing said record-producing element when said acceleration ceases and said core subsides to a lower position.
- 25 5. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 30 6. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 35 7. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 40 8. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 45 9. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 50 10. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 55 11. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 60 12. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 65 13. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 70 14. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated
- 75 15. Means for timing the record-producing element of an inclinometer, comprising: a solenoid and a core arranged to be elevated thereby and to subside slowly when said solenoid is deenergized; a vibrator unit for completing an electrical circuit in response to acceleration; brush means moving with said core for completing an electrical circuit through said vibrator and said solenoid whereby said core is maintained in a relatively elevated

position so long as said acceleration recurs; means cooperating with said brush means to complete a second electrical circuit energizing said record-producing element when said acceleration ceases and said core subsides to a lower position, and means for deenergizing said solenoid and breaking said second circuit when said record has been made.

6. Means for timing the record-producing element of an inclinometer, comprising: an electrical circuit including the actuating means for said record-producing element and means carried by a movable member for making and breaking said circuit; means responsive to acceleration of said inclinometer for maintaining said movable member in a position at which said circuit is interrupted so long as said acceleration recurs, and means actuated by gravity and operating when said acceleration ceases for moving said movable member to a position at which said circuit is completed and through said position to a position at which further movement of said member is inhibited.

7. Means for timing the record-producing element of an inclinometer, comprising: an electrical circuit including the actuating means for said record producing element and means carried by a movable member for making and breaking said circuit; means responsive to acceleration of said inclinometer for maintaining said movable member in a position at which said circuit is interrupted so long as said acceleration recurs, and means restrained by the flow of liquid through an orifice for moving said movable member through a position at which said circuit is completed to a position at which said circuit is permanently interrupted when said acceleration ceases.

8. In an inclinometer: a tubular housing; a pendulum centrally suspended in said housing; a record member; a slidable support for said member whereby said member is rendered movable toward said pendulum; recording means associated with said pendulum whereby its position relative to said member is recorded upon said member in response to said movement; an electromagnet arranged to actuate said support toward said pendulum and thereby to record said position, and automatic means responsive to cessation of vibration of said inclinometer and operatively associated with said electromagnet for producing a single energization of said electromagnet and for preventing a repetition of said energization.

9. In an inclinometer: a tubular housing; a pendulum centrally suspended in said housing; a record member; a slidable support for said member whereby said member is rendered movable to-

ward said pendulum; recording means associated with said pendulum whereby its position relative to said member is recorded upon said member in response to said movement; an electromagnet arranged to actuate said support toward said pendulum and thereby to record said position; means to energize said electromagnet; means for delaying said energization until said inclinometer comes to rest, and means responsive to cessation of vibration of said inclinometer and operatively associated with said electromagnet for preventing a repetition of said recording movement.

10. In an inclinometer: a tubular housing; a pendulum centrally suspended in said housing; a record member; a slidable support for said member whereby said member is rendered movable toward said pendulum; recording means associated with said pendulum whereby its position relative to said member is recorded upon said member in response to said movement; an electromagnet arranged to actuate said support toward said pendulum and thereby to record said position; means to energize said electromagnet; means responsive to acceleration for delaying said energization, and means responsive to cessation of acceleration and operatively associated with said electromagnet for preventing a repetition of said recording movement.

11. In an inclinometer: a pendulum having a pointed bob; a table slidable toward and away from said point; a record member removably placed on said table; means to actuate said table toward said point and thereby imprint a record of pendulum position on said record member, said means including an electromagnet; means to energize said electromagnet and actuate said table when said inclinometer comes to rest; means operative solely while said inclinometer is in motion for preventing said energization, and means responsive to cessation of said motion and operatively associated with said electromagnet for preventing a repetition of said energization.

PHILIP JONES.
